TOWEL HOLDER

Harold S. Rogers, 28 Clyde St., Poland, Ohio

Filed Oct. 22, 1965, Ser. No. 87,791

Term of patent 3½ years

(Cl. D4—3)

The side not shown is a mirror image of that shown in FIGURE 1 and the rear is substantially the same as the front shown.

I claim:

The ornamental design for a towel holder, as shown and described.
